BUCKLE

Sidney Stiffson, New York, N. Y.

Application April 22, 1932. Serial No. 606,844

6 Claims. (Cl. 241—12)

My invention relates to a device for holding the bosom or ordinary soft shirt front in its proper smooth position against the body of the wearer.

5 The ordinary shirt front has an inherent tendency to bulge and wrinkle when being worn and it is the principal object of this invention to provide means adapted especially to prevent this condition.

10 I accomplish the object of my invention by utilizing the adjustable buckle of each of the shoulder straps in a pair of suspenders and in affixing to the buckles thereof means capable of being attachably connected to the sides of a shirt front whereby the latter will be drawn to each side away from the center and held smoothly against the body.

Several embodiments of my invention are described in the following specification, set forth 20 in the appended claims, and illustratively exemplified in the accompanying drawing, in which Figure 1 is a front elevational view of a person wearing a soft bosom shirt, ordinary suspenders and the shirt fasteners carried thereby to hold 25 the front of the shirt in smooth conditions; Figure 2 is an elevational view of the suspender buckle equipped with one embodiment of my invention; Figure 3 is a substantially transverse sectional view taken on lines 3—3 of Figure 2; Figure 4 is a front elevational view of another 30 form of the invention; and Figure 5 is an elevational view of a still further modification.

Referring to the drawing, 10 denotes the ordinary bosom of a soft shirt and 11 the shoulder 35 straps of the usual type of suspenders or trouser supporters. Each shoulder strap 11 is provided with a buckle 12 for the purpose of adjusting the length of the strap.

40 According to the embodiment of the invention illustratively exemplified in Figures 1, 2 and 3, the buckle 12 comprises a back plate 13 provided with a clamp 14 on one face to engage the strands of the suspender forming the shoulder strap and a second clamp 15 on the opposite face to receive and engage a portion of the shirt front. The clamp 15 in the present instance consists in 45 an angular piece of metal, one arm thereof being shorter than the other and adapted at its free edge to engage the material of the shirt against the plate 13, while the longer arm forms the lever to swing and hold the shorter arm in closed position. Each end of the angle of the clamp 15 is provided with a short pin or projection 50 16 which pivots in an ear piece bent upright from the rear face of the plate 13.

In accordance with the form of the invention described in the foregoing, it will be noted that the means for engaging and holding the opposite sides of the shirt front are concealed behind the plate 13 so that in the event the waist coat is 60 removed the suspenders will merely display the ordinary buckle.

In accordance with the embodiment illustrated in Figure 4, the buckle is of the usual construction consisting of a back plate 17 and pivotally 65 mounted clamp or front plate 18. The means for engaging and holding the side of the shirt comprises a U-shaped wire piece 19 pivotally mounted along the upwardly disposed side of the back plate 17 and a flexible tab 20 carried at one end on the same plate and provided adjacent its free end with an upstanding knob 21 to separably engage 70 itself between the wire at the closed end of the piece 19. The portion of the shirt to be engaged is placed between the tab 20 and piece 19, and 75 the knob 21 is then projected with the shirt material into the loop of the wire piece. An arrangement of this character on each side of the shirt front causes the latter to be pulled away from the center towards each arm and provides an 80 even smooth distribution of the material of the shirt front against the body of the wearer.

The modification illustrated in Figure 5 includes 85 the flexible tab 20a, knob 21a, and wire loop 19a already described, but instead of these parts being attached directly to the buckle 11, they are mounted on the outer ends of short elastic strips 22, so as to give more resiliency to the shirt connection than is afforded by the suspender straps 90 alone.

Having now described my invention and the manner in which the same is utilized, what I claim and desire to secure by Letters Patent is:

1. An appliance for use in conjunction with a shirt and trousers for retaining them in proper 95 association with the body and with each other when simultaneously worn, which comprises: suspenders for supporting the trousers, the suspenders including a pair of bands extending frontally over the shirt, each band including devices for 100 making it effective to apply to the trousers a predetermined supporting force, the devices comprising means for adjusting the effective length of the band and means for effecting engagement of the band with the trousers, and an elastic member 105 associated with one of the devices of each band, the member of each band having means for engaging adjacent shirt material, the associated members of the opposed bands cooperating to apply 110 to the shirt front distending forces in opposite

directions for retaining the shirt front in a uniformly smoothened form.

2. In combination with suspenders for supporting trousers in position upon the body, the suspenders having buckles associated therewith, the suspenders being adapted to overlie a shirt worn in conjunction with trousers and each buckle having a plate positioned between shirt and suspender, and a clamp plate pivotally mounted on the plate for engaging a portion of the material of the shirt front between it and the plate, whereby the shirt front will be held smoothly against the body of the wearer.

3. In combination with suspenders for supporting trousers in position upon the body, the suspenders including a pair of members adapted to overlie a shirt worn in conjunction with trousers, means for engaging the sides of the shirt front to hold it smoothly against the body of the wearer, the means including flexible tabs each attached at an end to a member, each of the tabs being provided with a knob adjacent the other free end, and a U-shaped metal loop hinged on the member and arranged to cooperate with the knob for engaging and holding a portion of the shirt material interposed between knob and loop, whereby the shirt front will be held smoothly against the body of the wearer.

4. In combination with suspenders for supporting trousers in position upon the body, the suspenders including a pair of members adapted to overlie a shirt worn in conjunction with trousers, means for engaging the sides of the shirt

front to hold it smoothly against the body of the wearer, the means including flexible tabs, each of the tabs being provided with a knob adjacent a free end of the tab, a U-shaped metal loop hinged on the member and arranged to cooperate with the knob for engaging and holding a portion of the shirt material interposed between knob and loop, and a strip of elastic webbing between the other end of the tab and the member, whereby the shirt front will be held smoothly against the body of the wearer.

5. An appliance for use in conjunction with a shirt and trousers for retaining them in proper association with the body and with each other when simultaneously worn, which comprises: suspenders for supporting the trousers, the suspenders including a pair of bands extending frontally over the shirt and secured to the trousers, and a shirt-material engaging member secured to and extending from each band and within the outer margins of the bands.

6. An appliance for use in conjunction with a shirt and trousers for retaining them in proper association with the body and with each other when simultaneously worn, which comprises: suspenders for supporting the trousers, the suspenders including a pair of bands extending frontally over the shirt and secured to the trousers, and a shirt-material engaging member secured to each band, the members being extended toward each other from the bands.
